CEMENTING MACHINE

Fred C. Eastman, Marblehead, Mass., assignor to
United Shoe Machinery Corporation, Paterson,
N. J., a corporation of New Jersey

Application January 31, 1933, Serial No. 654,514

26 Claims. (Cl. 12—80)

My invention relates to machines for applying to articles a coating of cement, it being of especial utility in connection with work upon which it is desirable to lay a substantial thickness of adhesive along a band of definite width. An example of such work is furnished by the tops of tennis-shoes, the lower margins of which are to be cemented in preparation for the attachment of insoles.

10 An object of the invention is to effect the delivery of an ample quantity of the cement under ready control, and to so forward the work for its coating that the feeding means will not gather the coating-substance, to transfer it to the opposite side of the work from that being coated or to become clogged by such accumulation. To accomplish this purpose, I combine with a cement-applying member feeding means situated below and wholly at one side of the applying member 15 and arranged to engage the work to advance it to said applying member. For the applying means I prefer to employ a nozzle, thus insuring a free delivery of cement. For the feeding means one or more oscillatory members are desirable, 20 there being shown herein a plurality of feeding fingers movable into and out of engagement with the work, this movement being effected by actuating means which may consist of eccentrics carried by a rotatable shaft at one side of the 25 nozzle. The eccentrics are, as shown, arranged at different angles about their shaft to produce successive action of the fingers, thus giving a substantially continuous advance of the work. The movable feeding means may co-operate with 30 an abutment-surface against which the work is pressed, and I prefer to utilize for this purpose a surface upon the nozzle into co-operation with which the feeding fingers move from the side opposite the passage-opening of the nozzle. With 35 the cement-applying means and the work-feeding means thus related, any excess delivery or drip of cement will fall clear of the feeding members and, therefore, will not interfere with their action. As herein disclosed, this drip is received 40 by a receptacle beneath the nozzle, at one side of which receptacle the feeding means is located. The nozzle, in its movement between its active or delivering position and its inactive position, in which the flow of cement is cut off, may 45 be prevented from discharging the entire body of cement contained in the delivery-passage of the nozzle after the supply to said nozzle has ceased, by means, as a depression, in the passage for retaining a portion of said cement. In the 50 embodiment of the invention which I have chosen 55

to illustrate, the supply of cement is elevated from a receptacle through a conduit to the nozzle, said nozzle being mounted upon a work-supporting table carried upon the top of the receptacle. The quantity of cement delivered to the nozzle may be varied by a valve-controlled opening in the conduit.

One of a variety of forms which my invention may assume is illustrated in the accompanying drawings. Here,

Fig. 1 is a vertical section through my improved cementing machine;

Fig. 2, a section on the line II—II of Fig. 1;

Fig. 3, a top plan view of the applying and feeding elements; and

Fig. 4, a partial side elevation of the top or upper of a tennis-shoe which has been operated upon by the apparatus.

At 10 appears a cement-receptacle having at one side a covered filling spout 12 and at the bottom a valved drainage connection 14. The receptacle supports upon its top a casing 16 furnishing both a closure for said top and a mounting for the elements of the machine. The upper horizontal wall 18 of the casing serves as a table over which work-pieces are advanced to the cement-applying means and to the means which feeds the pieces automatically into co-operation with the applying means.

Considering first the means for applying cement to the work, the casing-wall 18 has a boss 20 horizontally bored to receive a spindle 22 rotatable about its axis by a handle 24. Extending through the spindle from a point within the boss to the end opposite the handle is a passage 25 (Fig. 2), opening into a nozzle 26 secured to the spindle. The nozzle has a depending portion 28 extended laterally and having at its lower edge a delivery-slot or opening 30 (Fig. 1). This opening is shown as situated above the open top 31 of a drip-receptacle 32 formed in the casing 16 and delivering to the main receptacle 10 over an inclined bottom wall 34 (Fig. 2). At the end of the passage 25 within the boss is a lateral opening 36 through the spindle, which, when said spindle is turned by its handle, may be moved into and out of registration with a vertical passage 38 in the casing-wall 18. This is to allow or to check the delivery of cement from the nozzle. To the passage 38 is connected a pipe or conduit 40 extending into the cement in the receptacle 10 and joined to the outlet of a rotary pump 42 (Fig. 1) supported upon a bracket 44 depending from the casing 16. The rotor of the pump has connected to it a vertical shaft 46 journaled in the 55

casing and geared at 48 to a horizontal shaft 50 turning in the side walls of said casing. To the shaft 50 power may be applied, either intermittently or continuously through any desired driving mechanism, said mechanism not being illustrated. To furnish means for regulating the discharge through the nozzle-opening 50 or to furnish a relief-flow if the nozzle-passage is closed at 36 by the rotation of the spindle 22, the vertical passage 38 (Fig. 2) has leading from it a horizontal passage 52 (Figs. 2 and 3) serving as a bypass and terminating in a discharge-opening 54 (Fig. 1) located above the receptacle 10. The size of the opening 54 may be varied by a valve 56, and thus the quantity of cement directed to the nozzle by its passages altered to obtain the desired delivery through the nozzle-opening to the work. With the nozzle in the operating position, the passage delivering through the depending portion 28 to the opening 30 is first downwardly inclined at 58 and then is curved upwardly and again down to the opening. The lower wall of the curved portion rises at 62 to substantially the level of the upper wall at the end of the inclined passage 58. Behind the upwardly extending wall 62 is formed a depression in which, when the machine is stopped after an operation upon a piece of work, the cement left to flow by gravity through the nozzle will be retained, that free to drip being the very limited amount just above the opening 30. A torsion-spring 64 surrounds the spindle 22 and normally holds the delivery portion of the nozzle in close proximity to the plane of the work-supporting surface of the table 18 for yieldable co-operation with the feeding mechanism, which will now be described.

The shaft 50 has fast upon it a series of eccentrics 66, located in a compartment 67 of the casing 16 extending outside the receptacle 10. These eccentrics are shown as arranged in three groups, disposed angularly above the shaft with respect to their maximum eccentricity 120 degrees apart. A set of the eccentrics made up of one of each of the three groups succeed one another side by side and are followed by other sets similarly disposed. Each eccentric acts upon a finger or feeding member 68 surrounding it, this enlarged surrounding portion being inclined forward, in the direction of advance of the work on the table 18, and up, to a work-contact-surface upon its upper edge, this surface preferably being toothed, as appears at 70 in Fig. 1, to furnish effective feeding engagement. All the fingers move in slots in a plate 71 (Fig. 2) set in the top of the compartment 67, and may be guided during their movement under the influence of the eccentrics by a single horizontal rod 72, extending between the walls of the casing and of the compartment and passing through inclined openings 74 in said fingers. Thus supported and under the influence of the eccentrics, the surfaces 70 travel in generally oval, inclined paths, up into contact with the work, forward to feed it beneath the nozzle-opening 30, down clear of the work and then back to the initial position. In this feeding action, the fingers co-operate with an approximately horizontal abutment-surface 76 upon the nozzle at the rear of the opening 30, this surface lying at or slightly above the work-supporting surface of the table 18. Such surface yieldably resists the upward pressure exerted by the fingers against the work, and the work is slid along it in the proper relation to the nozzle-opening to receive cement therefrom. Because of the operation of the fingers in successive groups by

their eccentricities and the relation to one another of the members of said groups, their feeding effect upon the work may be made continuous, one group coming into action at the time the previously acting group becomes ineffective. By the manner of spacing the fingers, this feeding effect for each group is distributed uniformly across the entire width of the work-area operated upon. It will be seen that the fingers terminate short of the field of action of the nozzle, they, with their actuating mechanism, being wholly at one side of the discharge of cement, so there is no possibility that their action will be interfered with by the drip. With respect to the nozzle and fingers, the work may be correctly located by an edge-gage 80 (Fig. 3) having its shank secured to the top of the table 18 by slot-and-screw connections 82. This allows the application of the band of cement upon different widths or transverse portions of the margin of the work.

To briefly outline the manner of using the machine, the operator, taking a shoe-top T which is to be coated at t with a band of cement, this being turned inside-out as illustrated in Fig. 4, elevates the nozzle 26 by the handle 24 and lays the work, with its outer side uppermost, upon the table 18 against the edge-gage 80. He thereupon allows the nozzle to be lowered by its spring 64 until the work is pressed yieldably by the nozzle-surface 76 against the toothed edges 70 of the fingers 68. The machine may then be started, and the pump 42 forces cement from the receptacle 10 into the nozzle 26, from which it flows, under the control of the relief or by-pass valve 56, through the opening 30 in a more or less heavy band along the margin of the shoe-top. As advanced by the fingers in their oscillation, the thus-traveling work is guided by the operator against the edge-gage 80 until its entire margin has been encircled, when the machine is stopped. The supply from the receptacle 10 ceases and the cement which is still in the nozzle is, in the main, held from delivery by the wall 62. The operator then swings up the nozzle by the handle, removes the coated work, and the machine is ready for operation upon another shoe-top. Any flow or drip from the nozzle beyond the edge of the work falls directly into the receptacle 32 and flows back to the source, without possibility of being transferred to the feeding mechanism, which is entirely separated from it laterally, and to the under side of the work. If desired, the apparatus may have the pump and feeding mechanism operated continuously, the closure of the opening 36 by the elevation of the nozzle stopping the delivery of cement.

Having described my invention, what I claim as new and desire to secure by Letters Patent of the United States is:

1. In a cementing machine, a cement-apply- 60
ing member, a work support, and feeding means
situated below the work support and wholly at
one side of the applying member and arranged
to engage the work and move it forward along
the support to receive the action of said applying 65
member.

2. In a cementing machine for flat blanks, a work table, a nozzle provided with a cement-delivering opening above the table, and work-feeding means situated below the nozzle and table and in advance of the opening thereby to engage a blank on the table and feed it forward to the nozzle.

3. In a cementing machine, a nozzle provided with a cement-delivering opening and an abut- 75

- ment to the rear of the opening, an actuating member situated at one side of and to the rear of the opening, and a feeding member movable by the actuating member and engaging the work only at the side of the nozzle-opening toward the actuating member and cooperating with said abutment to feed the work forward to the nozzle opening.
4. In a cementing machine, a receptacle for cement, a cement-applying member supplied therefrom, an actuating member situated at one side of the applying member, and an oscillatory feeding member movable by the actuating member and extending into engagement with the work adjacent to the applying member.
5. In a cementing machine, a receptacle for cement, a cement-applying member supplied therefrom, an actuating member situated at one side of the applying member, and an oscillatory feeding member movable by the actuating member and extending into engagement with the work adjacent to the applying member, the forward end of the feeding member terminating at a point short of the field of action of said cement-applying member.
6. In a cementing machine, a cement-applying member, feeding means situated below and wholly at one side of the applying member and arranged to engage the work and give it a movement of translation forward to receive the action of said applying member, and means situated in advance of the feeding means to receive the drip from the applying member.
7. In a cementing machine, a nozzle provided with a cement-delivering opening, work-feeding means situated below the nozzle and entirely separated laterally from the opening for giving the work a movement of translation, and a receptacle beneath the nozzle-opening to receive the drip therefrom.
8. In a cementing machine, a cement-applying member acting upon the upper face of the work, a movable toothed feeding member for advancing the work and movable in its work-advancing action into and out of contact with the lower face of said work, and means for oscillating said toothed member.
9. In a cementing machine, a cement-applying member acting upon one face of the work, a plurality of feeding members mounted for feeding movement into and out of contact with the opposite face of the work, and means for moving the members for alternate successive engagement with the work to feed it.
10. In a cementing machine, a cement-applying member acting upon one face of the work, a plurality of feeding members mounted for feeding movement into and out of contact with the opposite face of the work, the members being arranged in groups, and means for oscillating the groups successively into engagement with the work to feed it.
11. In a cementing machine, a cement-applying member acting upon the upper face of the work, a plurality of feeding members mounted for oscillatory feeding movement into and out of contact with the lower face of the work, the members being arranged in groups, and means for moving the groups successively into engagement with the work to feed it, the members of each group being separated from one another by the members of other groups.
12. In a cementing machine, a cement receptacle, a cement-applying member supplied therefrom and acting upon the upper face of the work,
- a shaft rotatable below the work, an eccentric carried by the shaft, and a feeding finger mounted for oscillation by the eccentric repeatedly into and out of engagement with a piece of work thereby to feed it past the applying member.
13. In a cementing machine, a cement-applying member acting upon the upper face of the work, a shaft rotatable below the work, eccentrics secured at different angles about the shaft, and feeding fingers movable by the eccentrics and acting upon the work at different times.
14. In a cementing machine, a cement-applying member applying a stripe of cement progressively to the upper face of the work, a shaft rotatable below the work, eccentrics carried by the shaft, feeding fingers movable by the eccentrics and successively engaging the work to feed it forward past said applying member, and a guide member common to the fingers.
15. In a cementing machine, cement-applying means, abutment means associated with the applying means and having at its under side a work-contact-surface, and an oscillatory feeding member arranged to press the work up against the contact-surface of the abutment.
16. In a cementing machine, cement-applying means, abutment means associated with the applying means and having at its under side a work-contact-surface, a mounting permitting the abutment means to yield upwardly, and a member mounted for oscillatory feeding movement arranged also to press the work up against the contact-surface.
17. In a cementing machine, cement-applying means, abutment means associated with the applying means and having a work-contact-surface, and a feeding member mounted for oscillatory movement in an inclined direction thereby to feed a piece of work forward toward the applying member and upwardly into co-operation with the contact-surface.
18. In a cementing machine, an applying nozzle having a cement-delivering opening and a work-contact-surface extending at one side of the opening, and a feeding member mounted for movement forward and to press the work intermittently against the nozzle-surface.
19. In a cementing machine, an applying nozzle having a cement-delivering opening and a work-contact-surface extending at one side of the opening, a pivotal mounting for the nozzle, a spring arranged to turn the nozzle upon its mounting toward the work, and a feeding member mounted for movement forward and to press the work intermittently against the nozzle-surface.
20. In a cementing machine, an applying nozzle having a cement-delivering opening and a substantially horizontal work-contact-surface adjacent to the opening at the under side of the nozzle, and a feeding member movable intermittently into engagement with the work beneath the surface thereof and from the side of the work opposite the delivering opening.
21. In a cementing machine, a table, a nozzle yieldably mounted above the table and having a cement-delivering opening and an abutment-surface extending from the opening along the table, and feeding fingers movable from beneath the table into work-feeding relation to the abutment-surface.
22. In a cementing machine, a table, a nozzle pivoted to move into and out of applying position above the table and having a cement-deliv-

ering opening and an abutment-surface extending from the opening along the table, means for yieldably maintaining the nozzle in its applying position, and feeding fingers movable from beneath the table into work-feeding relation to the abutment-surface.

23. In a cementing machine, a nozzle having a cement-delivering opening, a cement-receptacle below the nozzle, means for supplying cement from the receptacle to the nozzle, a drip-receptacle situated beneath the nozzle-opening and communicating with said cement-receptacle, and feeding means coacting with a portion of the nozzle at a region laterally displaced from the drip-receptacle constructed and arranged to feed the work forward under the nozzle and over the drip-receptacle.

24. In a cementing machine, a cement-receptacle, a drip-receptacle, a nozzle having a cement-delivering opening situated above the drip-receptacle and an abutment-surface extending from the opening to one side of said drip-recep-

tacle, feeding fingers movable into co-operation with the abutment-surface, and means for supplying cement from its receptacle to the nozzle.

25. In a cementing machine, a cement-receptacle, a table to support blanks of sheet material and carried upon the top of the receptacle, a nozzle mounted upon the table, feeding means mounted below the table to feed blanks past the nozzle, a pump operating in the receptacle to elevate cement to the nozzle, and a supply-conduit connecting the pump and nozzle. 5 10

26. In a cementing machine, a cement-receptacle, a table to support blanks of sheet material and carried upon the top of the receptacle, a nozzle mounted upon the table and having a cement-delivering opening above a piece of work on the table, said table having an opening arranged to return drip from the nozzle to the receptacle, a pump operating in the receptacle to elevate cement to the nozzle, and a supply-conduit connecting the pump and nozzle. 15 20

FRED C. EASTMAN.
